US00D851595S

(12) **United States Design Patent** (10) **Patent No.:** **US D851,595 S**
Chen (45) **Date of Patent:** **** Jun. 18, 2019**

(54) **POWER CONNECTOR**

(71) Applicant: **Zhejiang Shijian Import and Export Co., Ltd.**, Shenzhen (CN)

(72) Inventor: **Xiuying Chen**, Shenzhen (CN)

(**) Term: **15 Years**

(21) Appl. No.: **29/680,552**

(22) Filed: **Feb. 18, 2019**

(51) **LOC (11) Cl.** **13-03**

(52) **U.S. Cl.**

USPC **D13/133**

(58) **Field of Classification Search**

(57) **CLAIM**

The ornamental design for a power connector, as shown and described.

DESCRIPTION

FIG. 1 is a first perspective view of a power connector showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The dashed or broken lines shown in the drawings depict portions of the power connector in which the design is embodied that form no part of the claimed design.

1 Claim, 8 Drawing Sheets
